WINDOW CONSTRUCTION

William Owen, Pittsburgh, Pa., assignor to Pittsburgh Plate Glass Company, Allegheny County, Pa., a corporation of Pennsylvania

Application April 22, 1938, Serial No. 203,570

9 Claims. (Cl. 189—78)

The invention relates to window constructions of the type employing rubber strips under compression for holding the glazing unit removably in position in the sash or frame. It has for its 5 principal objects the provision of an improved construction of the type specified, which will permit the more ready and convenient application and removal of the rubber strips. Heretofore, in the use of rubber holding strips, it has been necessary to force a portion of the cross section of 10 the holding strip through a throat in the frame, and in order to make the construction secure, the amount of deformation of the strip in order to get it positioned has been such that much effort 15 and time is required for the assembly, particularly on the part of an unskilled worker. The present invention is designed to obviate this objection by providing a structure in which the assembly may be performed in two steps neither of which pre- 20 sents any difficulty, a main holding strip being first applied and then tightened by a secondary strip which deforms the first strip so as to secure the necessary holding effect with respect to the sash and a suitable sealing pressure by one of 25 the strips upon the glass. Certain embodiments of the invention are illustrated in the accompanying drawing, wherein:

Figure 1 is a front elevation of a car window embodying the invention. Fig. 2 is a section on 30 the line II—II of Fig. 1. And Figs. 3 to 7 are sections similar to Fig. 2, but showing modifications.

Referring to Figs. 1 and 2, the numeral 8 designates the sash or frame, and 9 is the glazing unit in the form of a sheet or plate of window glass. 35 The portion of the sash which carries the edges of the plate 9 is in the form of a channel having a back flange 10 which backs up the edge of the glass plate around its periphery. 11 is the front flange of the channel which is substantially shorter than the flange 10 so as to provide clearance 40 for the movement of the glass plate into and out of position. A strip 12 of rubber of angular cross section serves to cushion the edge of the plate in the sash.

45 The glass plate is secured in position in the sash by means of the rubber holding strip 13 which fits down into the channel with its base portion 14 under a slight amount of compression. Extending longitudinally of the strip is a slot 15, which is closed or nearly so when the strip is put 50 into position. After the strip is positioned, a second strip 16 is forced down into the slot spreading the strip 13, so that it is yieldingly held in the channel on one side and against the edge of the 55 plate 9 on the other side, thus securely locking

the parts in the assembled relation shown. The strip 16 is preferably of a material harder than the strip 13, so that the most of the deformation which occurs, due to the assembly, occurs in the strip 13. Hard rubber is a suitable material for 5 this strip, and a relatively hard strip of this character is more easily forced into position in a slot than a strip of soft rubber. Other materials which might be substituted for the hard rubber are fiber or one of the synthetic resins, such as 10 vinyl acetal or Bakelite. The strip 13 may be made all in one piece, but is preferably made in two pieces in a window of the type shown in Fig. 1, the two pieces meeting along the lines 17, 17. Similarly, the strip 16 may be made all in one 15 piece, but is preferably made in two pieces corresponding in longitudinal dimensions to the sections of the member 13.

In making the assembly, the glass plate 9 is first positioned in its rabbet in the frame 8 and 20 the strips 13 are pushed into position. There is no difficulty about this operation, since the amount of deformation in order to get the members 13 into position, is relatively slight. After this assembly has been made, the wedge strips 16 25 are pushed into position, as indicated in Fig. 2. This part of the assembly is also relatively easy, as all that is necessary is to start the wedge portion into the slot 15 at one end of such strip and then progressively push it in, the wedge shape of 30 the member 16 facilitating this assembly. When the parts are assembled, the member 13 is placed under compression, such that it is very securely 35 held in place and exerts substantial pressure against the plates 9 in opposition to the backing up flange 10. In disassembling the parts, it is only necessary to start the removal of one of the strips 16 at the end, after which it is very easily pulled out, as is also the strip 13 after the wedge strip 16 is removed.

40 Fig. 3 illustrates a modification, in which the plate 9 is held in the sash 8 by means of the two strip members 18 and 19. These members are both of soft rubber, and the method of assembly follows that heretofore described, the main strip 45 18 being first positioned in the channel with its base 20 under a slight degree of compression, after which the wedge member 19 is pushed down into position, being locked by friction and by the interlocking shoulders at 21. In this case, the 50 wedge member 19 is of soft rubber instead of being of hard material, since it is desirable to make good sealing contact with the glass.

In the modification of Fig. 4, the pane 9 is held in its sash 10 by means of the two strips 55

22 and 23, 22 being the main strip and 23 the wedge member. A lip 24 is preferably provided for covering the strip 23 when the parts are in assembled relation. In this case, as in the Fig. 5 construction, the wedge member 23 is preferably of soft rubber the same as the strip 22. After the strip 22 is applied, the lip 24 is pulled back and the strip 23 of circular cross section is wedged into the recess, thus deforming the member 22, so that it is held firmly in its channel and a sealing contact is secured between the member 23 and the face of the pane 9.

In the construction of Fig. 5, the pane 9 is held in its sash 8 by means similar to those shown in Fig. 2 except that the wedge member 25, which fits into the slot 26 in the rubber strip 27, is of circular cross section instead of being of triangular cross section. The strip 25 is of a material which is relatively harder than the strip 27, and in this case, a wire or hard woven cord may be used in place of the materials referred to in connection with Figs. 1 and 2 if desired.

Fig. 6 discloses a construction in which the pane 28 is held in its sash 29 by means of the spring clips 30 acting in conjunction with the rubber strips 31. After the spring clips are positioned, the rubber members 31 are wedged into position as shown, thus forcing the arms of the spring clips tightly against the bottom of the channel in the frame and against the face of the plate 28, the strip 31 functioning in the same manner as heretofore pointed out in connection with the strip 16 of Fig. 2. The strip 31 is preferably so proportioned that when positioned, as indicated in Fig. 6, it completely covers the spring clips and bears at its edges against the flange 32 and against the face of the glass plate 28.

Fig. 7 illustrates another modification showing the application of the invention in connection with double glazing and wherein 33, 33 are the glass panes and 34 is the frame or sash in which the edges are seated with the spacer 35 therebetween. The main holding strips are the rubber members 37, 37 which fit down into the frame as shown. The lips 38 of the strips 37 are caused to press strongly against the outer faces of the panes 33 by the use of wedge members 39 which are preferably of hard rubber and fit into grooves in the members 37 and bear at their lower sides against the flanges 40 of the channel. The wedges 39 are inserted after the rubber strips 38 are positioned and serve to deform the members 39, so that the necessary sealing pressure is applied to the faces of the glass panes.

55 What I claim is:

1. In combination in a window construction, a glazing unit, a sash of channel form having on one side a flange which backs up the edge of the unit and on the other side a shorter flange to permit the placing and removal of the unit past it and spaced forwardly of the front face of the unit thus providing a channel between the face of the unit at its edge and said shorter flange, a resilient removable strip seated in such last channel, and a second removable wedge strip engaging and deforming the first strip and causing one of said strips to press yieldingly against the edge of the glazing unit in opposition to the flange of the channel which backs up the edge of the unit.

2. In combination in a window construction, a glazing unit, a sash of channel form having on one side a flange which backs up the edge of the unit and on the other side a shorter flange to permit the placing and removal of the unit

past it and spaced forwardly of the front face of the unit thus providing a channel between the face of the unit at its edge and said shorter flange, a resilient removable strip seated in such last channel, and a second removable wedge strip engaging and deforming the first strip and causing one of said strips to press yieldingly against the edge of the glazing unit in opposition to the flange of the channel which backs up the edge of the unit. 10

3. In combination in a window construction, a glazing unit, a sash of channel form having on one side a flange which backs up the edge of the unit and on the other side a shorter flange to permit the placing and removal of the unit past it and spaced forwardly of the front face of the unit thus providing a channel between the face of the unit at its edge and said shorter flange, a rubber strip seated in such last channel under compression, and a second strip engaging and deforming the first strip and causing one of said strips to press yieldingly against the edge of the glazing unit in opposition to the flange of the channel which backs up the edge of the unit. 20

4. In combination in a window construction, a glazing unit, a sash of channel form having on one side a flange which backs up the edge of the unit and on the other side a shorter flange to permit the placing and removal of the unit past it and spaced forwardly of the front face of the unit thus providing a channel between the face of the unit at its edge and said shorter flange, a rubber strip seated in such last channel under compression and a second strip of rubber engaging the first strip and under compression and causing one of said strips to press yieldingly against the edge of the glazing unit in opposition to the flange of the channel which backs up the edge of the unit. 30

5. In combination in a window construction, a glazing unit, a sash of channel form having on one side a flange which backs up the edge of the unit and on the other side a shorter flange to permit the placing and removal of the unit past it and spaced forwardly of the front face of the unit thus providing a channel between the face of the unit at its edge and said shorter flange, a rubber strip seated in such last channel under compression and provided with a slot extending longitudinally thereof, and a second removable strip of harder material than the rubber wedged into said slot so as to deform the rubber strip and cause it to press yieldingly against the edge of the glazing unit in opposition to the flange of the channel which backs up the edge of the unit. 40

6. In combination in a window construction, a glazing unit, a sash of channel form having on one side a flange which backs up the edge of the unit and on the other side a shorter flange to permit the placing and removal of the unit past it and spaced forwardly of the front face of the unit thus providing a channel between the face of the unit at its edge and said shorter flange, a rubber strip seated in such last channel under compression and provided with a slot extending longitudinally thereof, and a second removable strip of harder material than the rubber and of triangular cross section wedged into said slot so as to deform the rubber strip and cause it to press yieldingly against the edge of the glazing unit in opposition to the flange of the channel which backs up the edge of the unit. 50

7. In combination in a window construction, a glazing unit, a sash of channel form having on

- one side a flange which backs up the edge of the unit and on the other side a shorter flange to permit the placing and removal of the front face of the unit thus providing a channel between the 5 face of the unit at its edge and said shorter flange, a rubber strip seated in such last channel under compression, and a second strip of rubber under compression wedged between the first strip and the edge of the unit in opposition to the flange 10 of the channel which backs up the edge of the unit.
8. In combination in a window construction, a glazing unit, a sash of channel form having on one side a flange which backs up the edge of the 15 unit and on the other side a shorter flange to permit the placing and removal of the unit past it and spaced forwardly of the front face of the unit, thus providing a channel between the face of the unit at its edge and said shorter flange, a 20 rubber strip seated in such last channel under compression, and a second strip of rubber under

compression and of triangular cross section wedged between the first strip and the edge of the unit in opposition to the flange of the channel which backs up the edge of the unit.

9. In combination in a window construction, 5 a glazing unit, a sash of channel form having on one side a flange which backs up the edge of the unit and on the other side a shorter flange to permit the placing and removal of the unit past it and spaced forwardly of the front face of the 10 unit, thus providing a channel between the face of the unit at its edge and said shorter flange, a rubber strip seated in such last channel under compression, and a second strip of rubber under compression wedged between the first strip and 15 said shorter flange of the channel to cause the first strip to press yieldingly against the edge of the glazing unit in opposition to the flange of the channel which backs up the edge of the unit.

20 WILLIAM OWEN.
